UNITED STATES PATENT OFFICE.

TRUMAN J. PARKER, OF DALLAS, TEXAS.

STEAM-BOILER.

1,274,759.

Specification of Letters Patent.

Patented Aug. 6, 1918.

Application filed August 25, 1917. Serial No. 188,124.

To all whom it may concern:

Be it known that I, TRUMAN J. PARKER, a citizen of the United States, residing at Dallas, in the county of Dallas and State of Texas, have invented new and useful Improvements in Steam-Boilers, of which the following is a specification.

This invention relates to steam boilers and aims to provide means whereby the heat from the fire box will be directed around the walls of the water chamber in a manner to traverse the entire area of said walls.

Another object of the invention is to provide means for positioning the water chamber so that all of its walls will be exposed, the construction being such as to direct the heat as it leaves the fire box around the inside wall of the water chamber, the draft causing the heat to travel around and contact with the outside walls of said chamber before reaching the atmosphere.

The invention further consists of the novel manner of constructing the boiler so as to permit of convenient access to the water chamber for cleaning the same, the said chamber being also removable in order to conveniently remove accumulations of soot from the walls of the boiler.

With the above and other objects in view, the invention consists of the following novel combination and arrangement of parts, hereinafter more fully described and illustrated in the accompanying drawings, in which—

Figure 1 is a front elevation of a boiler constructed in accordance with the present invention;

Fig. 2 is a vertical longitudinal sectional view on the line 2—2 of Fig. 1;

Fig. 3 is a vertical transverse sectional view on the line 3—3 of Fig. 2;

Fig. 4 is a detail sectional view on the line 4—4 of Fig. 2; and

Fig. 5 is a fragmentary sectional view on the line 5—5 of Fig. 2.

Referring to the drawings in detail, similar characters of reference denote corresponding parts throughout the several views.

In the drawings, there is illustrated a boiler which may be of the locomotive or stationary type, the invention being susceptible of application to boilers of either form. This boiler includes a water chamber 10 composed of spaced walls 11 and 12, the

latter wall being spaced within the former as illustrated in the drawings.

This water chamber is mounted within the preferably cylindrical casing 13, which is spaced from the outer wall 11 of the chamber 10, so as to provide a passage 14 entirely surrounding the water chamber. The casing 13 has spaced therefrom upon the inside, a wall 15, which contains a dead air space 16 to provide an insulation to prevent the escape of heat through the casing 13. The casing 13 may be formed in any suitable manner and if desired may be further insulated by providing spaced inner and outer walls 17 and 18, the space between these walls being filled with suitable insulating material 19.

The casing 13 may be supported in any suitable manner in accordance with the type of boiler, so that it is not deemed necessary to illustrate the supports of the same.

Located within the space formed by the inner wall 12 is a fire box 20, a grate 21 and an ash pit 22, so that a suitable source of heat may be provided for heating the water within the chamber 10. This source of heat is located within the bottom of the space formed by the inner wall 12, and diametrically opposite this source of heat and formed in the walls of the chamber 10 is a passage 23, formed by a slot extending practically the entire length of the water chamber. This slot permits of the passage of the heat therethrough after it has traversed the wall 12, the heat then entering the passage 14 and being forced downwardly around the outer wall 11 of the chamber 10 as indicated by the arrows on Fig. 3 of the drawings. Formed within the bottom of the casing 13 is a longitudinally disposed passage 24, which communicates at the rear of the casing with a smoke stack 25. The rear end wall 26 of the water chamber 10 is also spaced in the rear wall 27 of the casing to provide a passage 28, along which the heat will pass in its passage to the smoke stack 25.

It will thus be seen that the course of the draft directs the heat units around all of the inside and outside walls of the water chamber, heating the water therein in a short space of time and resulting in a great saving of fuel. The walls of the water chamber may be so regulated as to cause steam to be quickly generated.

The chamber 10 is removably mounted

within the casing and is supported therein in spaced relation to said casing through the medium of a skeleton support 29, provided at spaced intervals throughout the 5 length of the boiler. The front wall 30 of the boiler is formed with removable plates 31, which may be secured to the said wall in any desired way, this plate being of a sufficient size to permit of the movement of 10 the water chamber. Carried by this plate and extending into the chamber 10 is an annular flange 32. Also formed within the plate 31 is a fuel opening 33, which is closed by a door 34. Located beneath this fuel 15 opening is a door 35, provided for the convenient removal of the ashes. Extending through the plate 31, preferably at each side of the door 35 is an air or steam pipe 36, which extends along the under side of the 20 grate 21, in order to provide a forced draft for the fire. Water is supplied to the chamber 10 through the medium of a filling pipe 37, which communicates with the said chamber from each side of the longitudinally disposed passage 23 as shown in Figs. 4 and 5 of the drawings. This pipe 37 is formed in sections, so that the upper section thereof may be removed to permit of the removal of 25 the water chamber.

30 The front wall of the boiler casing may be provided with the usual steam and air gages and safety guide.

It is thought that from the foregoing description when taken in connection with the

accompanying drawings, the construction, 35 operation and advantages of the invention will be apparent. The right is reserved to make such changes in the form and proportion thereof as will fall within the scope of the claim hereto appended.

40 Having described the invention, what is claimed is:

A steam boiler comprising an outer cylindrical casing, a lower longitudinally extending passage projecting from and communicating with the interior of the casing at the bottom thereof, a vertically disposed outlet flue communicating with one end of said passage, a water chamber formed of inner and outer spaced walls arranged concentrically with and spaced from the inner wall of the casing to provide a heat circulating bottom, communicating with the lower longitudinal passage, a central heating chamber formed by the inner wall of the water chamber, an upper longitudinally disposed passage extending through the upper portion of the water chamber to establish communication between the heating chamber and the heat circulating chamber and a vertically disposed passage formed by spacing the rear wall of the water chamber from the rear wall of the casing for establishing communication between the heating chamber and the flue through the upper longitudinally disposed passage.

45 In testimony whereof I affix my signature.

TRUMAN J. PARKER.
